UNITED STATES PATENT OFFICE.

AUSTIN S. GRIMMER, OF BROOKLYN, NEW YORK.

BILL HOLDER.

Application filed June 9, 1922. Serial No. 566,970.

To all whom it may concern:

Be it known that I, AUSTIN S. GRIMMER, a citizen of the United States, a resident of Brooklyn, in the county of Kings and State of New York, have invented certain new and useful Improvements in Bill Holders, of which the following is a specification.

This invention relates to a bill holder and more particularly a bill holder so constructed that the free ends of the bill are exposed to view and examination.

An object of the invention is to provide a bill holder which will firmly hold bills in a secure manner and yet enable them to be exposed to view for the purpose of selecting any desired bill. Another object of the invention is to so construct the bill holder as to enable a person carrying the same to readily extract any bill without removing the others or disarranging them. Another object of the invention is to facilitate the insertion of the bills in the holder by creasing them. A still further object is to so construct the holder so as to accommodate any number of bills. Other objects will appear hereinafter.

The invention in its preferred embodiment is illustrated in the accompanying drawings which form part of this specification and in which—

Fig. 1 represents the holder in its flat or extended position, looking down on the top thereof;

Fig. 2 represents the rear or underside of the hinged plate 3,

Fig. 3 shows the holder with inserted bills before turning down the ends thereof with plate 3,

Fig. 4 shows the holder folded up for insertion in the pocket with a stack of bills held by the folder, and

Fig. 5 shows the underside of the holder with a stack of bills contained therein.

In said drawings there are shown three plates 1, 2 and 3, hinged together as shown by hinges 4 and 5 which are provided with springs to normally maintain the plates in the flat position in a single plane as shown in Figure 1. The plate 2 is hinged to the plate 1 so as to turn downwardly and the plate 3 is turned upwardly as viewed in Figure 1. Each plate can swing or turn only through an angle of 180°. They are preferably formed of metal with a leather or fabric covering but they may, of course, be formed of any other stiff or rigid material.

At the right hand edge of the plate 1 and at the lower side thereof, is attached a band or flexible backing 6 whose other end 7 is provided with a clip 8; and a tongue 9 is attached intermediate the ends of the band. Over the top surface of the plate 2 there is provided a holding means 10 comprising a suitable band or strip which may be of leather or fabric, and this is attached so as to permit the said band 6 to pass between it and the plate 2, the tongue 9 serving to pull the band 6 outwardly and the clip 8 serving to catch the edge of the band or strip 10 to prevent further outward motion. A pocketbook 11 for coins may be mounted above said strip 10.

The plate 3 has slidably mounted thereupon another sliding plate or member 12 which may be of metal. At the outer edge of the plate 3 is a slot 13 for receiving a clamp or catch 14 on the plate 1 when the plate 3 is folded over on the plate 1. A tongue 15 is mounted on the underside of the plate 3, and a second tongue 16 is attached to the band 6 by a pivot 17, the two being provided with means for fastening them together denoted by the pivot 18. The bills are designated by the numeral 19. Strips 20 are attached to the band 6 on the inside thereof in order to provide a suitable attachment for the tongue 16, but this construction is optional.

In using this device a stack of bills is taken for insertion between the band 6 and the plates 1 and 2 and the tongue 9 is pulled out to make room for their insertion. To facilitate this operation the plates 1 and 2 may be bent toward each other and the bills may be slightly creased longitudinally along their center. The ends of the bills are brought against the end of the tongue 15 and the clip 8 is then pulled in so that the band 6 will tightly grip the bills. Thereupon the plate 3 is swung down and clasped by a spring catch 13, 14. The sliding plate 12 should now be adjusted so that the tongue 15 will be just snug over the ends of the bills. For this purpose also bills themselves should be so placed in the bill holder as to provide for a tight holding by the tongues, or the bills may be adjusted in the bill holder with reference to the position of the sliding plate 12. When it is now desired to extract a bill at the top of the stack of bills (as looking down upon Fig. 3) it is merely necessary to seize the bill and pull it out

for the other bills will not be disarranged since they are gripped on both sides with bills while the bill seized is only gripped on one side by a bill. When, on the other hand, it is desired to extract a bill from the interior of the stack of bills the following operation is preferable: The plate 3 should first be unsnapped, the bills on either side of the bill desired should be bent back 10 against the holder, the bills and holder should then be seized and slightly flexed on the hinges 4 when it will be found that the bill may be readily extracted without moving the other bills. This action is due to the increased frictions developed among the bills folded back while the bill to be removed is largely freed from these frictions so that it can be moved without disarrangement.

20 As many apparently different embodiments of this invention may be made without departing from the spirit thereof it is to be understood that I do not intend to limit myself to the above specific embodiment thereof except as indicated in the claims of this patent.

I claim:

1. A bill holder comprising a plate having a band attached thereto and positioned beneath it, a second plate hinged to the first plate at its side to turn downwardly and means tending to hold it in the same plane, and a strip over the second plate to receive beneath it the said band.

35 2. A bill holder comprising a plate having a flexible backing attached to its side; a second plate hinged to the first plate at its other side to turn downwardly, and means tending to hold it in the same plane; and a flap on the said backing adapted to fold over on to the second plate, and means for holding said flap when so folded over.

45 3. A bill holder comprising a plate having a flexible backing attached to its side; a second plate hinged to the first plate at its other side to turn downwardly, and means tending to hold it in the same plane; a flap on the said backing adapted to fold over on to the second plate, and means for holding said flap when so folded over; and a third plate hinged to said first plate.

55 4. A bill holder comprising a plate having a band attached thereto and positioned beneath it, a second plate hinged to the first plate at its side to turn downwardly and means tending to hold it in the same plane, a strip over the second plate to receive beneath it the said band and a tongue and clip on the end of the band to adjust its position with respect to the strip.

65 5. A bill holder comprising a plate having a band attached thereto and positioned beneath it, a second plate hinged to the first plate at its side to turn downwardly and means tending to hold it in the same plane, a

strip over the second plate to receive beneath it the said band, a tongue and clip on the end of the band to adjust its position with respect to the strip and a receptacle for coins mounted above the strip.

6. A bill holder comprising a plate having a band attached thereto and positioned beneath it, a second plate hinged to the first plate at its side to turn downwardly and means tending to hold it in the same plane, 75 a strip over the second plate to receive beneath it the said band, a third plate hinged to the edge of the first plate adjacent the second plate and also having means tending to hold it in the same plane with the first plate and also to clasp the third plate down on the first plate.

7. A bill holder comprising a plate having a band attached thereto and positioned beneath it, a second plate hinged to the first plate at its side to turn downwardly and means tending to hold it in the same plane, 85 a strip over the second plate to receive beneath it the said band, a third plate hinged to the edge of the first plate adjacent the second plate and also having means tending to hold it in the same plane with the first plate 90 also to clasp the third plate down on the first plate and means on said third plate to hold the ends of the bills against said plate.

8. A bill holder comprising a plate having a band attached thereto and positioned beneath it, a second plate hinged to the first plate at its side to turn downwardly and 100 means tending to hold it in the same plane, a strip over the second plate to receive beneath it the said band, a third plate hinged to the edge of the first plate adjacent the second plate and also having means tending to hold it in the same plane with the first plate 105 and also to clasp the third plate down on the first plate, and a tongue on the third plate and a tongue on the band provided with means for clasping them together for the 110 purpose of firmly holding the bills in place.

9. A bill holder comprising a plate having a band attached thereto and positioned beneath it, a second plate hinged to the first plate at its side to turn downwardly and 115 means tending to hold it in the same plane, a strip over the second plate to receive beneath it the said band, a third plate hinged to the edge of the first plate adjacent the second plate and also having means tending to hold it in the same plane with the first plate 120 and also to clasp the third plate down on the first plate, a tongue on the third plate and a tongue on the band provided with means for clasping them together for the 125 purpose of firmly holding the ends of the bills against said third plate, and a sliding plate mounted on the third plate for adjustment of the tongue.

10. A bill holder comprising a plate hav-

ing a band attached thereto and positioned beneath it, a second plate hinged to the first plate at its side to turn downwardly and means tending to hold it in the same plane, a strip over the second plate to receive beneath it the said band, a tongue and a clip on the end of the band to adjust its position, a third plate hinged to the edge of the first plate adjacent the second plate and also provided with means tending to maintain it in a plane position, and means on said third plate to hold in firm contact therewith the ends of the bills.

11. A bill holder comprising a plate having a flexible backing attached to its side; a second plate hinged to the first plate at its other side to turn downwardly, and means tending to hold it in the same plane; a flap on the said backing adapted to fold over on to the second plate, and means for holding said flap when so folded over; and a third plate hinged to said first plate, and having a flap attached to said backing.

12. A bill holder comprising a plate having a band attached thereto and positioned beneath it, a second plate hinged to the first plate at its side to turn downwardly and means tending to hold it in the same plane, a strip over the second plate to receive beneath it the said band, a third plate hinged to the edge of the first plate adjacent the second plate and also having means tending

to hold it in the same plane with the first plate also to clasp the third plate down on the first plate and means on said third plate 35 to hold the ends of the bills against said plate, the three plates being so proportioned that when folded the bills will present a triple fold substantially as shown.

13. A bill holder comprising a plate having a bill holding band attached thereto, a second plate hinged to the first plate at its side turning downwardly and means tending to hold it in the same plane, and means for securing said band in a desired position 40 to hold the bills.

14. A bill holder comprising a plate having a flexible backing attached to its side; a second plate hinged to the first plate at its other side to turn downwardly, and means 50 tending to hold it in the same plane; a flap on the said backing adapted to fold over on to the second plate, and means for holding said flap when so folded over; and a third plate hinged to said first plate, and having a tongue attached to said backing, and a sliding plate mounted on said third plate acting in conjunction with tongue on the back of the third plate to regulate the position 55 of the bills.

In testimony that I claim the foregoing, I have hereunto set my hand this 6th day of June, 1922.

AUSTIN S. GRIMMER.
